UNITED STATES PATENT OFFICE

LEO SOLINGER, OF NEW YORK, N. Y., ASSIGNOR TO EAGLE PENCIL COMPANY, OF NEW YORK, N. Y., A CORPORATION OF DELAWARE

TRUMP INDICATOR

Application filed January 18, 1927. Serial No. 161,717.

This invention relates generally to pencils and has particular reference to combined pencils and indicators.

One object of the invention is to provide a pencil suitable for keeping the score of a card game and which may also be used as a trump indicator.

Another object of the invention is to provide a device of the character mentioned which, while highly satisfactory for the purposes intended, may be manufactured and sold profitably at a low retail price.

A preferred embodiment of the invention is illustrated in the drawing accompanying and forming a part of this specification.

In said drawing, Fig. 1 shows one of the combined pencils and indicators as it appears when viewed from an angle at which the diamond and club sections of the construction are visible.

Fig. 2 is like Fig. 1 except that it shows the heart and spade sections of the construction.

Fig. 3 is a group of details showing separately the construction of various pieces which are shown in completely assembled relation in Figs. 1 and 2.

The representative embodiment of the invention illustrated in the drawing comprises a cylindrical pencil body 10 and contains the usual marking material 11. The periphery or external surface of the body of the pencil is divided into four longitudinal red and black panels 12, 13, 14 and 15 of equal width and arranged so that the colors alternate. The body of the pencil at the end opposite the writing end is reduced slightly in diameter, as shown at 16, to form a seat for a shell or eraser tip 17 of any suitable material. The eraser tip 17 is formed to provide four flat faces 18, 19, 20 and 21 which are substantially equal in extent. The material of the tip or shell 17 is cut away in each of the four faces so as to form openings each having the outline of one of the four card pips designating the four suits in a pack of playing cards.

A rectangular block 22 having its four sides composed of or containing material to give the sides alternating red and black faces 23 and 24 is inserted within the eraser tip 17 in such a position as to bring a colored face in

alignment with one of the cut-away portions of the tip 17 with an appropriately colored panel or face on the block exposed through each of the suit indicia openings. The block 22 may be held in position by a block 25 of rubber or other suitable erasing material in such a way as to be firmly held in the eraser tip.

It is apparent that the preferred construction which has been described affords a combined pencil and indicator which may be used for recording scores of card games and which may be laid on any suitable surface with the proper suit indicia uppermost to indicate the current trump, and that the construction is one which may be produced at a relatively lower cost than similar articles previously on the market.

While the embodiment shown and described is a highly satisfactory one in the respects stated, it is apparent that the invention is capable of other embodiments such as come within the scope of the claims which follow.

What is claimed is:

1. An article of the character described comprising in combination a body having longitudinal panels colored to correspond to the colors of the suits in a pack of playing cards, a shell secured to one end of the body and having cut away portions in alignment with the correspondingly colored panels and shaped to represent clubs, diamonds, spades and hearts, and panels exposed through such cut away portions colored to correspond to the suits represented by the respective cut away portions.

2. An article of the character described comprising a cylindrical body having on its surface four longitudinal panels colored alternately red and black, a shell attached to one end of the body comprising four flat sides each cut away in alignment with one of the appropriately colored panels on the cylindrical body to represent one of the suits in a pack of playing cards, and a rectangular block within the shell having alternate red and black faces in alignment with the correspondingly colored panels on the cylindrical body.

and exposed by the cut away portions in the shell.

3. An article of the character described comprising a rod-like member, a metal shell attached to one end of the member having four flat sides each cut away to form an opening representing one of the four suits in a pack of playing cards, a rectangular block inserted within the shell and having portions adjacent said openings colored to correspond with the suit indicating openings, and means for holding said block in position in the shell.

4. An article of the character described comprising a rod-like member having on its surface four longitudinal panels colored alternately red and black, a shell attached to one end of the member having four flat sides each cut away in alignment with an appropriately colored panel on the member to represent one of the four suits in a pack of playing cards, a rectangular block within the shell having alternate red and black faces in alignment with the correspondingly colored panels on the rod-like member, and a second block of material retaining the first block in the shell and projecting from said shell.

In testimony whereof I hereto affix my signature.

LEO SOLINGER.
